UNITED STATES PATENT OFFICE

172,910

TILE CUTTER

Harold L. Vennell, Haddonfield, N. J.

Application May 7, 1954, Serial No. 30,368

Term of patent 14 years

(Cl. 54—13)

To all whom it may concern:

Be it known that I, Harold L. Vennell, a citizen of the United States, residing at Haddonfield, county of Camden, State of New Jersey, have invented a new, original, and ornamental Design for a Tile Cutter, of which the following is the specification, reference being had to the accompanying drawing, forming a part hereof.

Figure 1 is a perspective view of a tile cutter showing my new design;

Figure 2 is a top plan view thereof;

Figure 3 is a side elevational view, and

Figure 4 is a rear end elevational view thereof.

I claim:

The ornamental design for a tile cutter, substantially as shown.
